UNITED STATES PATENT OFFICE.

ROBERT I. PARKS, OF WASHINGTON, DISTRICT OF COLUMBIA.

COMBINATION WATER-BOTTLE AND SYRINGE.

1,230,318.

Specification of Letters Patent. Patented June 19, 1917.

Application filed July 10, 1916. Serial No. 108,402.

To all whom it may concern:

Be it known that I, ROBERT I. PARKS, a citizen of the United States, residing at Washington, in the District of Columbia, 5 have invented certain useful Improvements in Combination Water-Bottles and Syringes, of which the following is a specification, reference being had therein to the accompanying drawing.

10 This invention relates to hot water bottles and more especially to the class of combination hot water bottles and syringes.

15 The primary object of the invention is the provision of an article of this character wherein the body thereof is preferably made from metal formed in two sections joined to each other through the medium of an overlapped seam formed at the meeting edges of said sections thereby producing 20 a structure which possesses strength and durability thus increasing the longevity of the article.

25 Another object of the invention is the provision of an article of this character wherein the body thereof is constructed in a novel manner so that a cage or container is removably held therein for receiving antiseptic material which is readily dissolved on the introduction of hot water into the body 30 thereof, thereby preventing the cooling of the water should the same be placed within a separate receptacle and the antiseptic material dropped therein for the dissolving of the same within the water in the ordinary well known manner.

35 A further object of the invention is the provision of an article of this character wherein the construction thereof permits the converting of the article into either a hot water bottle or fountain syringe.

40 A still further object of the invention is the provision of an article of this character which is simple in construction, neat, attractive in appearance, compact, thoroughly reliable and efficient in its purposes and inexpensive in manufacture.

45 With these and other objects in view, the invention consists in the features of construction, combination and arrangement of 50 parts as will be hereinafter fully described, illustrated in the accompanying drawing

and pointed out in the claims herein appended.

In accompanying drawing:

Figure 1 is a side elevation of a combination water bottle and syringe constructed in accordance with the invention the body being partly broken away. 55

Fig. 2 is an edge elevation thereof.

Fig. 3 is a fragmentary enlarged vertical longitudinal sectional view through one corner of the body. 60

Fig. 4 is a view similar to Fig. 3 through the other corner of the body.

Fig. 5 is a side elevation of the cage or 65 container for the disinfectant.

Fig. 6 is an end elevation thereof.

Similar reference characters indicate corresponding parts throughout the several views in the drawing. 70

Referring to the drawing in detail, the combination water bottle and syringe comprises a substantially rectangular shaped hollow flattened body A, preferably formed in two sections 5 and 6 respectively which 75 are connected together through the medium of an over-lap seam 7 at their meeting edges, the seam being formed in any approved manner so as to avoid any possibility of leakage at the joint of the sections. The 80 body A is preferably made from metal although the same may be made from any other suitable material giving strength and durability thereto.

Two opposed corners of the body A are 85 flattened in contra-distinction to the remaining two rounded corners of the body to present inset diagonal corners 8 having formed therein exteriorly threaded annular necks 9 on which are detachably fitted removable caps 10 which are internally threaded to engage the threaded necks and in each cap is carried a resilient disk 11 forming a washer so as to afford a tight joint when the cap is applied to the neck to 95 avoid leakage therethrough.

At one side of each neck 9 and integrally formed with the body A or mounted thereon is an eye 12 to which is connected a retaining chain 13 the same being also connected in any suitable manner to the cap 10 so that on the removal of the latter the same 100

will not become detached or separated from the body thereby eliminating the possibility of the loss of the cap in the use of the bottle.

One of the chains 13 has, engaged with 5 several of its links, a ring 14 which is used for hanging the bottle upon a hook or other support when said bottle is not in use.

Formed in one flattened angular corner 8 of the body A of the bottle within the neck 10 9 is a hole 15 which is of slightly less size than the diameter of the said neck to form a shoulder 16 within the latter concentrically of the hole 15, while removably introduced in the hole is a reticulated cylindrical 15 or tubiform cage or container 17 which forms a disinfectant holder, one end of the cage or container being open and has concentrically thereof an annular flange or rim 18 which is adapted to rest upon the shoulder 16 when the cage or container is inserted through the hole 15 to protrude within the body A of the device. It is of course understood that the cap 10 is removed when the cage or container 17 is inserted in the hole 20 25 15 and upon placing the disinfectant within said container or receiver the required quantity of water can be poured through the container or receiver for dissolving the disinfectant therein and filling the bottle.

30 Bridging the open end of the receiver or container 17 and secured to or integral with the body thereof is a cross bar 19 which forms a hand hold for convenience in inserting the receiver or container within the 35 body and its removal therefrom as will be obvious.

40 Mounted in or formed integral with the opposite flat angle corner 8 of the body A, centrally with respect to the neck thereof and protruding outwardly, is a discharge nipple 20 on which is adapted to be telescoped or engaged one end of a flexible tube ordinarily used in a fountain syringe and when said tube is mounted thereon it is 45 clearly apparent that the article can be used as a fountain syringe in the usual well known manner.

Of course it is understood that the tube is inserted upon the nipple 20 after the removal of the cap 10 closing said nipple prior to the filling of the bottle.

One of the caps 10 carrying the washer 11 closes the nipple 20 the washer being designed to contact with the outer end of the 55 nipple to provide a tight joint for eliminating leakage while the other cap 10 closes the hole 15 and its washer 11 contacts with the neck 9 for forming a tight joint to avoid leakage through the said hole as will be 60 obvious.

Each cap has its marginal edge corrugated or scalloped as at 21 so that a firm grip may be had upon the cap for the tightening of the same upon each neck or its 65 removal therefrom in a convenient manner.

By reason of the inset opposed corners 8 of the body A and the particular conformation of the caps the arranged configuration of these corners are consistent or substantially similar to the rounded remaining corners of the body A of the bottle thereby rendering the said bottle neat and attractive in appearance.

In the use of the article, assuming that a hot water bottle is needed, the body A is 70 filled with hot water through the hole 15, it being understood of course that the receiver or container can remain within the hole as it will not interfere with the pouring of the water into the body, yet the disinfectant need not be within the receiver or container and after the filling of the body with the required quantity of water it can be readily used as a hot water bottle.

Now should the article be used as a fountain syringe the cap 10 closing the nipple 20 is removed prior to the filling of the body A and the flexible tube carrying the syringe nozzle as usual, is telescoped upon said nipple although if desired, the body can be 80 filled with water containing a disinfectant which latter is placed within the receiver or container 17 and is dissolved on the pouring of the water into the body prior to the application of the flexible tube and this is 85 accomplished after the cap is placed upon the body for closing the opening 15 and the body is inverted. The invention is not restricted to the manner of application of the flexible tube nor the particular uses of the 90 article as this is optional with the user.

The disinfectant receiver or container 17 can remain within the body A when the same is employed as a hot water bottle and in this event the disinfectant is not introduced into the receiver or container.

From the foregoing it is thought that the construction and manner of use of the article will be clearly understood and therefore a more extended explanation has been 105 omitted.

What is claimed is:

1. An article of the class described, comprising a substantially rectangular hollow body having a pair of upper and lower 110 diagonally opposed flat corners, cap attaching flanges secured to the outer faces of said flat corners, the upper flat face having a relatively large opening therethrough within the adjacent cap attaching flange, a 115 nipple secured to the lower flat face within the adjacent cap attaching flange and projecting beyond the same, and caps detachably mounted on said flanges for sealing the upper flange and for sealing the open 120 end of said nipple.

2. An article of the character described, comprising a hollow body provided with upper and lower flattened faces having openings therethrough, cap attaching flanges 125

secured upon the outer sides of said flat faces, a reticulated receptacle fitting through the opening of said upper flat face and projecting into the hollow body, a nipple secured to the lower flat face within said flange, and caps detachably mounted on said flanges for sealing the upper flange

and holding said receptacle in place and for engagement with the open end of said nipple to seal the same.

10

In testimony whereof I affix my signature.

ROBERT I. PARKS.
